(57) **CLAIM**

The ornamental design for a charger for a portable radio, as shown and described.

DESCRIPTION

FIG. 1 is a perspective view of a charger for portable radio showing our new design;

FIG. 2 is a left view of the new design;

FIG. 3 is a right view of the new design;

FIG. 4 is a front view of the new design;

FIG. 5 is a rear view of the new design;

FIG. 6 is a top view of the new design; and,

FIG. 7 is a bottom view of the new design.

The broken lines in the figures depict portions of the article which form no part of the claimed design.

1 Claim, 6 Drawing Sheets
